UNITED STATES PATENT OFFICE.

KARL F. G. MAIER, OF SOUTH ASHBURNHAM, AND ELLIOTT J. McKNIGHT, OF GARDNER,
MASSACHUSETTS, ASSIGNORS TO L. G. McKNIGHT & SON COMPANY, OF GARDNER,
MASSACHUSETTS, A CORPORATION OF MAINE.

SANDING-MACHINE.

1,305,916.

Specification of Letters Patent. Patented June 3, 1919.

Application filed October 31, 1918. Serial No. 260,424.

To all whom it may concern:

Be it known that we, KARL F. G. MAIER and ELLIOTT J. McKNIGHT, citizens of the United States, residing at South Ashburnham and Gardner, respectively, county of Worcester, and State of Massachusetts, have invented an Improvement in Sanding-Machines, of which the following description, in connection with the accompanying drawings, is a specification, like characters on the drawings representing like parts.

The invention to be hereinafter described relates to sanding machines, and more particularly to that type of sanding machines for treating the curved surfaces of wooden strips.

In the copending application of Karl F. G. Maier, Serial No. 189,009, filed August 30, 1917, is shown, described and claimed a sanding machine having a sanding roll, a curved table for supporting the curved strips, such, for example, as chair backs, flexible feeding members conveniently in the form of sprocket chains connected by transverse bars for feeding the curved strips over the sanding roll, and a presser member or roll opposed to the sanding roll for holding the strips to the sanding roll.

This is an efficient, practical machine for treating the surfaces of wooden strips curved on the same or approximately the same radius, but it sometimes happens that the curvature of the strips will vary to such an extent that when passing simultaneously between the sanding roll and the presser roll, the latter will press upon a strip of shorter radius to the exclusion of the strip of another radius, or at any rate, exert an objectionably greater pressure upon the former than upon the latter.

One of the aims and purpose of the present invention, therefore, is to provide means for pressing a plurality of strips simultaneously against the sanding roll with sufficient pressure to cause the roll to properly treat the surfaces of the strips in case the latter have equal or different radii of curvature. In the present instance of the invention, this feature is carried into practical effect by the provision of a series of arms or members which are individually pressed by springs toward the sanding roll, the con-

struction being such that the strips are always properly pressed against the sanding roll.

Another object of the invention is to provide a support for the pressure fingers or members which may be adjusted toward or from the sanding roll to vary the distance of said fingers or members therefrom to conform to strips of different thickness as desired, and to vary the degree of pressure exerted by the fingers or members on the strips. Another object is to provide individual springs for the pressure fingers or members, and means for varying the tension of the springs to compensate for the wear thereon, and to differentially press the fingers or members if desired.

Another object of the invention is to provide a station or receiver for the strips located in the path of the feeding means therefore, so that the strips may be picked up by the feeding means and conveyed from the station or receiver to and between the sanding roll and pressure device.

Other objects of the invention are to provide means to facilitate entrance of the pieces to be treated between the sanding roll and pressure fingers or members; to provide means for contributing to the support of the pieces as they pass from between the sanding roll and pressure fingers or members; and to provide improved carrier means for feeding the pieces between the pressure fingers or members having provision for adjusting and tensioning the same as required.

With the aforesaid and other objects in view, the character of the invention will be best understood by reference to the following description of one good form thereof shown in the accompanying drawings, wherein:

Figure 1 is a perspective view of one part of a machine embodying the invention, in which the sanding roll is located above the pressure fingers;

Fig. 2 on an enlarged scale is a vertical section showing a portion of the sanding roll, a portion of the table supporting the pieces, and the pressure fingers arranged beneath the roll;

Fig. 3 is a plan of the pressure fingers and the support therefor;

Fig. 4 is a view of the pressure fingers and their support, partly in front elevation and partly in section;

Fig. 5 on an enlarged scale is a detail of 5 one of the tensioning devices for the fingers;

Fig. 6 is a perspective view of a machine in which the sanding roll is located beneath the pressure fingers;

Fig. 7 is a plan of the yieldable table for 10 contributing to the support of the pieces as they pass from between the upper sanding roll and the pressure fingers; and

Fig. 8 is an end view of the table shown in Fig. 7.

15 Referring to the drawings, the machine shown therein as one good form of the invention, comprises a frame which may be of any desired character, and as illustrated in the present instance, comprises side 20 frames 1 and 3 (Fig. 1) connected by cross members 5 secured to said side frames, the construction being such that the frame will be suitable to support the operating parts.

The sanding roll, in the present instance 25 of the invention, comprises a cylinder 11 having a sanding or grinding surface 13 and secured to a horizontal shaft 15 which may be supported in bearings 17 mounted on the side frames of the machine. This shaft may 30 be provided with any suitable means for driving the same.

The machine is primarily intended to 35 treat the surface of curved strips which are to be fed to the sanding roll. To support the strips, a table 21 may be provided having a curved surface which may be substantially in conformity with the curved surfaces of the strips to be treated. In the present instance, this table is mounted between 40 the side frames of the machine, and extends from a point adjacent the bottom of said frames to a point somewhat beyond the sanding roll, and has a space 22 (Fig. 2) therein through which the pressure fingers or members to be described may project 45 as shown in Fig. 2.

Suitable means may be provided for feeding the strips over the table to and past the sanding roll. To accomplish this, in the 50 present instance, an endless carrier is provided conveniently in the form of a pair of sprocket chains 23 connected at intervals by transverse bars or feeding members 25 suitably secured to said chains. To guide these 55 chains in their transit, suitable guide means may be provided, in the present instance, in the form of guideways 27 having a curvature in substantial accordance with the curvature of the table. In order that the transverse bars may not ride directly upon or injure the curved surface of the supporting table, the guideways may be raised a short distance above the table, the construction being such that as the chains are moved to 60 feed the strips over the table to the sanding

roll, the transverse bars will ride closely adjacent to, but out of contact with the curved surface of the table.

The sprocket chains may be guided in their lower runs about sprocket wheels 29 fast 70 on a shaft 31 journaled in bearings in brackets 33 fixed to the side frames, and sprocket wheels 35 on stub shafts 36 carried by brackets 37 secured by bolts 38 to vertical faces 39 of the side frames, the heads of said bolts being adapted to slide in T-slots 41 in said side frames. The construction is such that these brackets may be vertically adjusted to give the sprocket chains the tension required.

80 Suitable means may be provided for driving the sprocket chains. To accomplish this, in the present instance, a driving shaft 43 is provided journaled in bearings carried by the frame and having a sprocket wheel 45 fast thereon connected by a sprocket chain 47 with a larger sprocket wheel 49 on the shaft 31 referred to. The shaft 43 may have a pulley 51 fast thereon connected by a belt 53 with a smaller pulley 55 fast on a shaft 57 journaled in bearings mounted on the side frames of the machine and driven by any suitable means as desired. To tighten the belt 53, an idler pulley 53^a may engage said belt and be carried at one end 95 of a lever 53^b fulcrumed on a pin 53^c on one of the side frames of the machine, the opposite end of said lever being provided with a spring handle 53^d adapted to interlock with and be held by a toothed sector 53^e in different positions of adjustment.

To contribute to the efficient treatment of the strips, the sanding roll may not only be rotated, but also may be reciprocated axially. To accomplish this, the shaft for said 105 roll may be connected to a yoke 57 on the upper end of a lever 59 fulcrumed intermediate its ends on a bracket 61 mounted on one of the side frames. The lower end of this lever is provided with a follower 63 which works in a cam groove in a drum 67 mounted on the driving shaft 43 referred to. The construction is such that the cam will rock said lever and reciprocate the sanding roll axially.

The station or receiver for supporting the strips in the path of the endless carrier, in the present instance, comprises a bar 69 mounted on arms 71 fast on a rock shaft 73 journaled in bearings in brackets 75 secured to the side frames of the machine. This receiver bar may be yieldingly pressed toward the work supporting table by a coil spring 77 encircling a pin and confined between an abutment 81 on one of said brackets and an arm 83 fast on said rock shaft. The construction is such that strips may be placed on the work supporting table with their lower ends resting against said receiver bar where they will remain until a

feed bar of the endless carrier approaches said receiver bar and rocks the same outward from the table, thereby allowing the lower ends of the strips to be picked up by the feed bar. Continued movement of the carrier will feed the strips upward along the curved surface of the table to the sanding roll.

The table and sanding roll are of a width sufficient to accommodate a plurality of 10 strips, in the present instance, four strips 84 are shown mounted on the work table with their lower ends resting on the receiver bar in readiness to be fed to the sanding roll. In some cases the radius of 15 curvature of all of the strips is the same, but in other cases the radii of curvature of the strips may vary more or less. An important feature of the invention, therefore, relates to means for properly pressing all 20 of the strips against the sanding roll, whether their radius of curvature is the same, or the radii of curvature are different. This means, in the present instance of the invention, comprises a series of members or 25 fingers 85 (Figs. 2, 3 and 4), each having a curved pressure portion 87 having a smooth surface adapted to bear on the under surfaces of the strips, and each finger or member may have a boss 89 loosely 30 mounted on a shaft 91 secured in brackets 93 projecting up from a carrier bar conveniently in the form of an angle bar 94 having its ends connected to blocks 95 which may be adjustable in uprights 97 mounted 35 in recesses 98 in the side frames of the machine.

To adjust these blocks in said uprights, screws 99 may be threaded to said blocks and journaled in bearings 101 in said uprights, said screws being suitably confined 40 against axial movement relative to said bearings. At the lower ends of said screws are bevel gears 103 meshing with bevel gears 105 fast on the ends of a transverse shaft 45 107 journaled in bearings in said uprights, said shaft being provided with a suitable hand wheel 111. The construction is such that the operator may turn the hand wheel and through the gears and screws described, 50 adjust the blocks and carrier bar for the pressure fingers up or down in the uprights as desired.

Suitable means may be provided for pressing said fingers or members against the 55 strips passing over the sanding roll. To accomplish this, in the present instance, each finger or member may have a shank 113 conveniently integral therewith projecting downward from the supporting shaft there- 60 for. Individual coil springs 115 may be provided for the fingers, said springs having hook 117 (Fig. 5) which may be anchored to the flange 119 of the finger carrier bar. The convolutions of the opposite 65 ends of the springs may be reduced in di-

ameter and receive the heads of screws 121 entered through holes in the finger shanks, and having thumb nuts 123 thereon, suitable washers 125 being confined between said nuts and said finger shanks. The construction is such that the springs tend to pull on said shanks and rock said fingers up against the strips between said fingers and the sanding roll. The shanks of said fingers may engage the edge of the carrier angle 70 bar therefor to limit the up movement of the pressure fingers and prevent the same from engaging the sanding roll when no strips are between said fingers and roll. The tension of said springs may be individually varied by adjusting the thumb nuts on their screws, and thus the pressure of the fingers may be individually varied so as to produce equal or differential pressures of 75 said fingers as desired. 80

In some cases it may be desirable to simultaneously and equally vary the pressures of the series of fingers. This may be accomplished by adjusting the carrier for said fingers upward or downward with respect 90 to the sanding roll.

From the construction described, it will be apparent that if the strips have different radii of curvature, the finger or fingers pressing on one strip will not be affected by 95 the finger or fingers pressing on another strip or strips. As a consequence, the strips will always be properly pressed toward the sanding roll to be efficiently treated thereby regardless of their radii of curvature. 100

Entrance of the strips between the sanding roll and fingers may be facilitated by a floating roller 127 (Fig. 1) having trunnions mounted in elongated bearings 129 on the side frames adjacent the sanding roll, the construction being such that the roller may move upward somewhat, but the weight of the roller will assist proper entrance of the pieces between the sanding roll and 105 fingers. 110

Suitable means may be provided to contribute to the support of the pieces as they emerge from between the sanding roll and fingers. To accomplish this, in the present instance, a curved table 135 (Figs. 1 and 7) 115 may be provided preferably of spring metal having a reverse bend 139 secured to a supporting bar 141 adapted to be adjustably connected to the side frames of the machine by screw bolts 143 entered through elongated 120 slots 145 in said bar. The construction is such that the pieces are pressed upward somewhat as they are fed outward past the sanding roll.

The part of the machine thus far described is adapted to sand or treat the convex surfaces of the curved pieces, but when the concave surfaces of the pieces are to be treated a modified form of the machine may be used in which the series of pressure fin- 125 130

gers or members will be above the sanding roll. This modification is shown in Fig. 6, and comprises a table 146, sanding roll 147, a series of pressure fingers 149 carried by a shaft 151 secured in brackets 153 on an angle bar 155 connected to blocks 157 adjustable in guideways in uprights 159 mounted on top of the side frames of the machine. The blocks are adjusted by screws 160 rotated by bevel gears 161 thereon meshing with bevel gears 163 on a cross shaft 165 journaled in bearings in brackets 167 on the uprights, said shaft having a hand wheel 169 fast thereon. The fingers have shanks 171 connected by coil springs 172 with the flange 173 of the angle bar 155. The construction is such that the fingers are yieldingly and independently pressed downward toward the sanding roll to efficiently press the concave faces of the pieces against said roll. The rest of this machine may be similar to the machine first described, and therefore, it is unnecessary to repeat a showing thereof in Fig. 6. The two machines may be arranged in tandem so that the convex and concave surfaces of the pieces may be progressively fed through the machine.

The operation of the machines will be readily understood from the foregoing description. The hand lever is operated to rock the idler pulley to tension the belt and cause the travel of the sprocket chains. Then the operator places the strips to be treated on the work supporting table of the first machine with their lower ends resting against the receiver bar. In the course of the travel of the carrier, a feed bar thereof will reach the receiver bar and engage the lower ends of the strips and feed the same up over the curved table between the sanding roll and the presser fingers, the latter serving to properly press the convex surfaces of the strips against the sanding roll so as to be efficiently treated thereby. Then the pieces may be fed between the sanding roll and pressure fingers of the second machine where the concave surfaces thereof are treated.

It will be understood that the invention is not limited to the specific embodiment shown, but that various deviations may be made therefrom without departing from the spirit and scope of the appended claims.

What is claimed is:—

55 1. In a machine for sanding surfaces of curved strips, the combination of a support having side frames, a curved table for supporting the strips, bearings on said side frames, a sanding roll for treating the strips 60 having horizontal shaft portions journaled in said bearings, a plurality of pressure fingers opposed to said roll, means independently to press said fingers toward said roll, and endless carriers mounted on said support having members to engage ends of the

strips and feed the same over the curved table between said sanding roll and pressure fingers.

2. In a machine for sanding surfaces of curved strips, the combination of a support, 70 a curved table thereon of a width sufficient to support a plurality of strips in side-to-side relation, a sanding roll for treating the strips disposed with its axis substantially horizontal, a shaft carried by said support, a series of pressure fingers fulcrumed on said shaft, springs co-operating with said fingers independently to press the side-to-side strips toward said roll, and means to feed the strips over the table between said sanding 75 roll and fingers.

3. In a machine for sanding surfaces of strips, the combination of a sanding roll, a support for the strips, means to feed the strips over said support to said rolls, a plurality of pressure members opposed to said roll, means to press said members individually toward said roll, and means to adjust said members bodily relatively to said roll. 80

4. In a machine for sanding surfaces of strips, the combination of a sanding roll, a support for the strips, a carrier, a plurality of pressure members mounted on said carrier, and means including screws at opposite ends of said carrier for adjusting the 90 pressure members relatively to said roll. 95

5. In a sanding machine for sanding surfaces of curved strips, the combination of a sanding roll, pressure means opposed to said roll for pressing the strips toward the 100 latter, a curved table for receiving the strips, a receiver for temporarily supporting the strips on said table, and feeding means for taking the strips from said receiver and for feeding the same over said table between 105 said sanding roll and pressure means.

6. In a sanding machine for sanding surfaces of curved strips, the combination of a sanding roll, a plurality of independent members opposed to said sanding roll for 110 pressing the strips thereto, a curved table for supporting the strips, a receiver for engagement with ends of the strips to support the same on said table, and feeding means for taking the strips from said receiver and 115 for feeding the same over said curved table between said members and said sanding roll.

7. In a sanding machine for sanding surfaces of curved strips, the combination of a sanding roll, pressure means for pressing the 120 strips toward said roll, a receiving station, a curved table extending from said receiving station toward said sanding roll, and an endless carrier having means for taking strips from said receiving station and for feeding the same over said table between said pressure means and sanding roll. 125

8. In a sanding machine for sanding surfaces of curved strips, the combination of a sanding roll, pressure means for pressing 130

strips toward said roll, a curved table for supporting the strips leading to said sanding roll, an endless carrier for conveying the strips over said table between said pressure means and sanding roll, and guide means for said endless carrier having provision for varying the tension of said carrier.

9. In a sanding machine for sanding surfaces of curved strips, the combination of a frame, a sanding roll mounted thereon, uprights on said frame, a series of pressure members carried by said uprights, spring means for pressing said members toward said sanding roll, a curved table mounted on said frame for supporting the strips, and an endless carrier having feeding members for engaging said strips to feed the same over said

curved table between said pressure members and sanding roll.

10. In a sanding machine for sanding surfaces of curved strips, the combination of a curved support, a sanding roll to act on pieces as they are moved over said support, presser members for pressing the pieces toward said roll to be treated thereby, means to feed the pieces over said support past said roll, and a floating roll to rest on the pieces and facilitate entrance thereof between said roll and members.

In testimony whereof, we have signed our names to this specification.

KARL F. G. MAIER.
ELLIOTT J. McKNIGHT.
